UNITED STATES PATENT OFFICE.

JACOB J. SOUDER, OF WASHINGTON, DISTRICT OF COLUMBIA.

METALLIC ROOF FOR RAILWAY-CARS.

1,215,213.

Specification of Letters Patent.

Patented Feb. 6, 1917.

Application filed November 20, 1915. Serial No. 62,495.

To all whom it may concern:

Be it known that I, JACOB J. SOUDER, (whose post-office address is 1417 F street northwest,) a citizen of the United States, 5 residing at Washington, in the District of Columbia, have invented certain new and useful Improvements in Metallic Roofs for Railway-Cars; and I do hereby declare the following to be a full, clear, and exact description of the invention, such as will enable others skilled in the art to which it appertains to make and use the same.

The invention relates to improvements in railway cars, and more particularly to the 15 roof construction of the same, and to the means for securing the latter on the body of the former.

The primary object of the invention is to provide a simplified construction of the character mentioned, and one in which the means, for securing the roof on the body of the car, admits of independent movement of the former with respect to the latter, when the car is in motion, whereby the usual rolling and twisting movement of the latter is 25 not transmitted to the former, as is the case in the present practice of rigidly securing the roof to the body of a car.

Another object of the invention is to provide a sectional metallic roof for cars, or the like, in which the several sections of the same are applied without the use of nails, screws, or solder, and which, after being assembled, may be independently removed, in 35 case of damage, without necessitating the unfastening or removal of the major portion of the roof.

A further object of the invention is to provide a car, and the roof carried thereby, 40 with means for preventing the transmittal of heat therethrough, whereby to practically eliminate the condensation of moisture, given off from grain or other perishable content of the car when subjected to such 45 heat, as from the rays of the sun, on the interior thereof, such as has heretofore proved to be a source of trouble, expense and loss, the rusting of the metal parts of the car, the replacing of destroyed or otherwise 50 ruined parts thereof, and the molding or otherwise destroying of the goods being transported.

With these and other objects in view, the invention resides in the certain new and 55 novel construction and arrangement of

parts, which will be hereinafter more fully described, set forth in the appended claims, and illustrated in the accompanying drawings, in which,

Figure 1 is a vertical transverse section of 60 a car provided with the improved roof,

Fig. 2 is a fragmentary longitudinal section showing the application of an end section or plate,

Fig. 3 is a perspective view showing the 65 several parts of the invention in position for assembly,

Fig. 4 is a fragmentary plan view showing the trusses positioned thereon, one of the trusses being shown in section,

Fig. 5 is a detail view of the truss securing device in position,

Fig. 6 is a perspective view of a pair of end roofing sections or plates, partly in section,

Fig. 7 is a fragmentary detail of the inner and outer members of a truss,

Fig. 8 is a fragmentary sectional detail showing the method of securing the running board supporting blocks in position,

Fig. 10 is a perspective view of a pair of clips adapted for securing the running board supporting blocks in position on the roof,

Fig. 9 is a fragmentary transverse section through one of the car stringers showing the 85 truss securing means positioned therein.

Reference being had to the accompanying drawings, in which similar characters of reference designate corresponding parts on the several views thereof, the numeral—10— 90 indicates a car body, of usual construction, including a belt rail—11— and upper plates or stringers—12—, upon the latter of which is to be secured the roof and its supporting trusses.

The roof construction comprises a plurality of inverted V-shaped trusses, arranged in spaced relation throughout the entire length of the body—10— and transversely thereof. These trusses each comprise an outer supporting member—13— of sheet metal bent to provide a substantially U-shaped portion—14—, and oppositely disposed flanges—15—, and an inner supporting member—16—, also of sheet metal, adapted to rest in the channel of the U-shaped outer member—14—. The inner member—16— is of a width to project above the oppositely disposed flanges—15—, of the outer member—13—, and 110

has its upper edge cut in a manner to provide alternately and oppositely disposed tongues —17—, normally overlying the flanges —15—. After the inner member 5 —16— has been properly positioned within the outer member —13—, it is to be secured therein by means of rivets —18—, passed through the two members as shown, or in any other suitable manner. The lower portions of the opposite ends of the trusses, 10 thus formed, are cutaway, as at —19—, and are formed with openings —20—, adjacent the cutaway portions, for the purpose to be hereinafter described.

15 For positioning and securing the trusses in spaced relation along the top of the car body —10—, there is provided bolt members —21—, each having a U-shaped head —22— adapted to loosely receive one end 20 of a truss and provided with openings, which, when alined with the opening —20—, also loosely receive a securing pin —23—. Each of the upper side stringers —12—, of the body —10—, are provided with a 25 series of alining mortises —24—, forming seats for supporting the U-shaped heads —22—, of the bolt members, the threaded shanks —25—, of the latter, being projected downwardly through suitable openings, and 30 secured therein by means of nuts —26—. Immediately above the mortises —24— are formed elongated mortises —27—, adapted to loosely retain the securing pins —23—, after they are properly engaged in the openings of the trusses and the heads of the bolt 35 members. Medially of the ends of the mortises —24— and —27—, and opening through the inner face of the stringers —12—, are formed slots —28— which 40 loosely receive the shorter or cutaway portions of the trusses, so that the flanges —15—, of the latter, projecting beyond the cutaway portions —19—, rest upon the upper face of the stringers —12—, and flush 45 therewith by reason of mortises —29— being formed in the stringers for the purpose.

Having thus positioned the several trusses, 50 the roof plates or sections are now to be assembled thereon. The oppositely disposed end plates or sections —30— and —31— are each, respectively, made to be fitted on at the right and left hand sides of the body —10—, and are of sheet metal, one end of a plate or section being bent 55 back upon itself to provide an inturned bead —32—, which is continuous with a similar bead —33—, formed along one side of the plate or section, and which beads are adapted to contact the outer faces of the 60 upper stringers of the car frame and project outwardly therefrom for a relatively short distance. The abutting ends of the plates or sections —30— and —31— are formed with upwardly projecting flanges 65 —34—, while the truss side of the plate or

section is also provided with an upwardly projecting flange —35— adapted to contact the adjacent wall of the inner supporting member —16— of the truss. The lower edge of each intermediate plate or section 70 —36— is formed to provide a bead —37—, corresponding to the beads —32— and —33—, of the end plates or sections —30— and —31—, and which, at one side or end thereof terminates in a projecting portion 75 —38— adapted to project around the adjacent end of a truss member and underlie the adjacent plate or section. The side edges of the intermediate plates or sections —36— are bent upward to provide flanges 80 —39—, which, when the plates or sections are positioned between the trusses, abut the adjacent wall of the inner supporting members —16— between the tongues —17— and the flanges —15—. The abutting ends of 85 the intermediate plates or sections —36— are each provided with upwardly projecting flanges —40—, the purpose of which, as well as that of the corresponding flanges —34— of the end plates or sections —30— 90 and —31—, will be hereinafter described.

After the plates or sections have been assembled, as before described, transverse cap-channels —41—, formed of sheet metal and bent substantially U-shaped and having 95 their side edges bent inwardly of the side walls thereof to provide flanges —42—, are threaded on the tongues —17—, one for each oppositely inclined portion of a truss, until they are fully positioned thereon. The 100 plates or sections are now secured in position by bending the cap-channels —41—, and the tongues —17— engaged thereby, inward against the opposite sides of the inner supporting member —16—, of the trusses. The 105 roof is now completed by forcing over the abutting flanges —34— and —40—, of the end and intermediate roof plates or sections —30—, —31—, and —36—, respectively, a cap-channel or clip —43—, which is of sheet 110 metal bent in suitable form to snugly engage over the said flanges.

To prevent excessive heat, as from the rays of the sun, affecting the content of a car, it is desired that the interior walls —44—, 115 of the body —10—, above the belt rail —11—, be lined or otherwise coated with a heat resisting material, such as asbestos or the like, also, that each end plate or section —30—, —31—, and intermediate plate 120 or section —36—, of the roof, be similarly lined or coated with asbestos, as at —45—, such coating or lining extending over the entire surface of the plates or sections, except that portion forming the beaded edge 125 thereof. It is, however, particularly desired that the lining extend over the contacting surfaces of the abutting flanges —34— and —40—, for preventing the transmittal of 130 heat from one section to the other, as well as

providing for a slight resiliency to the joint therebetween.

It is desirable that the roof, thus provided, be assembled on the body of the car after to the putting on of the sheathing or outer walls thereof, so as to permit the beads —32—, —33— and —37—, which overhang the stringers —12— as before mentioned, to abut the outer faces of the latter, for the purpose of having the upper ends or edges of the sheathing contact the under face of the beads, as at —46—, which arrangement allows for an air and weather-proof joint therebetween. A molding —47— may be broken around the upper edge of the sheathing, also in contact with the under face of the beads.

In the application of a roof of this type to a freight car, it is necessary that a running board, extending longitudinally thereof, be provided, and for this purpose wooden blocks —48—, grooved, as at —49— and —50—, to engage over the transverse and longitudinally extending seams of the roof, are positioned at the juncture therebetween, and held firmly in such position by means of metallic clips —51—. These clips —51— are substantially U-shaped in cross-section with the lower flange —52— inclined to conform to the pitch of the roof, and in the positioning and securing of the clips, the latter, prior to the bending downward of the transverse cap-channels —41—, and the tongues —17—, engaged thereby, is placed in abutting relation with respect to the roof section flanges —35—, —39—, as shown, so that the flange —52— is firmly secured when the cap-channels —41— are forced into locked position. The upper flanges —53—, of the clips —51—, engage the top face of the blocks —48— and are secured thereto by means of nails or screws, or in any other suitable manner, and are further secured in position by the running-boards —54— resting thereon, as shown in Fig. 1.

From the foregoing, it is to be noted, that the roof, thus constructed, is without solder, nails or screws being used to render it watertight, or to secure it in position, that undue straining or distorting of the roof, as has heretofore obtained when a car is in motion, is eliminated by reason of the loose connections interposed between the same and the body of the car, which means, at the same time, holds the roof in air and water-tight relation with respect to the body, that the sections or plates of the roof are interchangeable, and any section may be removed or replaced without the removal of the roof, or interfering with its adjacent section, and that the use of an inner lining on the roof sections or plates, and on the upper walls of the interior of the body, eliminates the destructive effect of heat, heretofore common in the known car structures.

Having thus fully described the invention, what is claimed, is:

1. As a new article of manufacture, a car-line for supporting roofing sections formed to provide a longitudinally extending channel, and a strip of sheet metal secured in said channel and co-extensive therewith, and extending upward therefrom, said strip being formed into alternate oppositely disposed flanges adapted to be bent into engagement with the roofing sections for securing the latter rigidly in position. 70

2. As a new article of manufacture, a car-line for supporting roofing sections formed of sheet metal bent to provide a substantially U-shaped channel portion, flanges formed at opposite sides of said channel portion and of a length to project beyond the planes of the opposite ends of the latter, a fastening means of sheet metal secured in said channel and co-extensive with said flanges, and means formed with said fastening means and adapted to be bent into engagement with the roofing sections for securing the latter rigidly in position. 80

3. As a new article of manufacture, a car-line for supporting roofing sections formed of sheet metal and bent to provide a substantially U-shaped channel portion, flanges formed at opposite sides of said channel portion and of a length to project beyond the planes of the opposite ends of the latter, a strip of sheet metal secured in said channel and co-extensive with said flanges and extending upward therefrom, and alternate oppositely disposed flange sections formed at the upper edge of said strip and adapted to be bent into engagement with the roofing sections for securing the latter rigidly in position. 95

4. A railway car comprising a body, a roof, of unitary construction, mounted for movement vertically of said body, vertically disposed U-headed bolt-members carried at opposite sides of said body, and means engaged in the U-heads of said bolt-members for loosely connecting the roof thereto. 100

5. A railway car comprising a body, car-lines spaced transversely of the body, sectional roofing elements carried by the car-lines and secured thereto, bolt-members carried at opposite sides of the body, U-shaped heads formed with said bolt-members and adapted to loosely receive the opposite ends of the car-lines, and a loosely fitting means connecting the carline ends with the U-shaped heads of the bolt-members, whereby the carlines, and the roofing elements carried thereby, have independent movement with respect to the body under normal running conditions. 115

6. A railway car comprising a body, a roof, of unitary construction, mounted for movement and vertically of said body, vertically disposed U-headed bolt members se- 120

4
cured within recesses formed in the top edges of the opposite sides of said body, and pins engaged in the **U**-heads of said bolt members for loosely connecting the roof thereto, 5 and retained in their engaged position by the surrounding walls of said recesses.

7. A railway car comprising a body having spaced recesses opening through the top edges of the opposite sides thereof, a roof, of 10 unitary construction, mounted for movement vertically of said body, elements secured in said body and projecting into said recesses, and means loosely connecting said roof to said elements, said means being retained in 15 engaged position by the walls of said recesses.

8. A railway car comprising a body having spaced recesses opening through the top edges of the opposite sides thereof, a roof, of 20 unitary construction, mounted for movement vertically of said body, **U**-headed bolts secured in the bottom wall of said recesses, and means engaged in the **U**-heads of said bolt members for loosely connecting said 25 roof in position, said means being retained in engaged position by the walls of said recesses.

9. A railway car comprising a body having spaced recesses formed in the top edges 30 of the opposite sides thereof, carlines spaced transversely of said body and overlying said recesses, sectional roofing elements carried by said carlines and secured thereto, bolt members secured in the bottom wall of said 35 recesses, **U**-shaped heads formed with said

bolt members and adapted to loosely receive the opposite ends of said carlines, and loosely fitting means connecting said carlines with said **U**-shaped heads of the bolt member, whereby the carlines and the roofing elements carried thereby, have independent movement with respect to the body under 40 normal running conditions.

10. In combination, a railway car body having spaced recesses formed in the top 45 edges thereof, carlines spaced transversely of said body, roofing sections secured to said carlines, depending portions formed with said carlines and projecting into said recesses, elements rigidly secured in said 50 recesses, and means connecting said depending portions of said carlines with said elements, said means admitting of a limited vertical movement to said carlines and the roofing elements carried thereby. 55

11. In combination, a railway car body having spaced recesses formed in the top edges thereof, carlines spaced transversely of said body, roofing sections rigidly secured to said carlines, depending portions formed 60 with said carlines and projecting into said recesses, elements rigidly secured in said recesses and engaging the projected ends of said depending portions of said carlines, and means connecting said elements and said depending portions, said means admitting of 65 a limited vertical movement to said carlines and the roofing elements carried thereby.

In testimony whereof I affix my signature.
JACOB J. SOUDER.
